UNITED STATES PATENT OFFICE.

LYMAN R. SWETT, OF BOSTON, MASSACHUSETTS.

HEATING DRUM.

Application filed November 16, 1923. Serial No. 675,117.

This invention relates to an improvement in heating drums, and more particularly to the type applicable to stove or furnace smoke whereby the heat carried through the flue may be transmitted to the drum and conducted by piping from the drum to any suitable source.

The invention consists of a tubular drum of sufficient size to envelope the smoke flue 10 of a stove or furnace, and is provided with an outlet nipple to which a pipe is attached for conducting the heated air from the drum to a suitable source. Mounted on the smoke flue are two heads, each made in sections, 15 for readily assembling of the heads and drum on the smoke flue. The heads are provided with an internal flange for supporting the ends of the drum.

The invention consists of certain other 20 novel features of construction and combinations of parts which will be hereinafter described and pointed out in the claims.

In the accompanying drawing—

Figure 1 is a view in side elevation showing the invention applied to a smoke pipe;

Figure 2 is a plan view; and

Figure 3 is an edge view of one of the sections of the head.

A stove or furnace smoke flue or pipe 5, 30 has mounted thereon at any suitable point throughout its length, a tubular drum 6, which is of greater diameter than the diameter of the smoke flue 5.

The drum 6 is supported on the flue 5 by means of heads, composed of two sections 7, 7. The heads are preferably cast, and each section is provided with a semi-circular outwardly projecting hub 8, which engages the smoke flue 5. The hub portion 8 of 40 each section is provided near the end thereof with a projection 9, whereby bolts 10 may be passed through the projections for fastening the heads on the smoke flue 5.

On the inner face of each head section 7 45 is formed a semi-circular flange or ring 11, which is located a short distance below the peripheral edge of the head. The flanges or rings 11 of the two heads support and engage the ends of the tubular drum 6. One 50 of the heads is fixed or fastened to the smoke flue 5 and an end of the drum 6 is placed thereon, then the other head is moved along the smoke flue until the flange 11 of the other head is in engagement with the other 55 end of the heating drum 6 when the head

sections 7 are clamped about the smoke flue by means of the bolt 9. Each section 7 of the heads is provided with a laterally extending ear 15 which is adapted to engage the adjacent edge of the adjacent section 60 for insuring the head sections being properly aligned when joined together and placed upon the smoke flue. One of the sections 7 of one of the heads is provided with an opening for the admission of air to the drum 65 6 which may be closed entirely by means of a pivoted damper 12 carried by the head and the size of the opening may be regulated by the movement of the damper. The heating drum 6 is provided with an outlet nipple 70 13 to which a pipe may be attached for conducting the heated air of the drum to a room or any other suitable place.

From the foregoing it will be seen that a simple attachment has been provided for 75 a smoke flue for extracting some of the heat in the flue gases which is generally wasted by passing through the smoke flue to the atmosphere and which device may be readily applied or removed at the convenience of 80 the owner.

Having described my invention what I claim as new and desire to secure by Letters Patent is:—

1. In a heating drum, the combination 85 with a smoke flue of a tubular drum surrounding the flue, sectional heads, each section being provided with a semi-circular hub at its inner edge, the hub of each section of a head being mounted upon the 90 flue, and means carried by the hubs for fastening the hubs of a head together on the flue, and flanges formed on the inner faces of each section of the heads for engaging the inner wall of the drum for supporting the 95 drum in spaced relation to the flue.

2. In a heating drum, the combination 100 with a smoke flue, of a tubular drum surrounding the smoke flue, heads removably mounted on the flue and of a diameter to fit within the drum for supporting it on the flue, each of said heads being made in sections, means for fastening the sections of each head together, one of the sections of one head being provided with an air 105 inlet opening, and a damper mounted on said section, for regulating the amount of air delivered to the drum.

LYMAN R. SWETT.
